UNITED STATES PATENT OFFICE.

BENJAMIN F. MAYO, OF SALEM, MASSACHUSETTS, ASSIGNOR TO THE MCKAY SHOE MACHINERY COMPANY, OF PORTLAND, MAINE, AND BOSTON, MASSACHUSETTS.

DESIGN FOR A PROTECTIVE SLUG.

SPECIFICATION forming part of Design No. 30,840, dated May 23, 1899.

Application filed April 26, 1899. Serial No. 714,585. Term of patent 14 years.

To all whom it may concern:

Be it known that I, BENJAMIN F. MAYO, a citizen of the United States, residing at Salem, in the county of Essex and Commonwealth of 5 Massachusetts, have invented and produced a new and original Design for a Protective Slug, of which the following is a specification.

Figure 1 is an end view of a protective slug, illustrating my design; and Fig. 2 is an elevation thereof viewed from the open end of the slug.

The leading feature of my design for a protective slug consists of an elongated body bent transversely to form wings, said wings 5 being inturned at their free ends to constitute a heart-shaped figure open at its larger end.

The protective slug comprises an elongated body bent transversely at *a* to form wings *b* *c*, said wings having their extremities in-curved, as at *d e*, to present a heart-shaped figure open at its larger end. 20

Having fully described my design, what I claim, and desire to secure by Letters Patent, is—

The design for a protective slug, substantially as herein shown and described.

In testimony whereof I have signed my name to this specification in the presence of two subscribing witnesses.

BENJAMIN F. MAYO.

Witnesses:

GEO. W. GREGORY,
MABEL PARTELOW.
